UNITED STATES PATENT OFFICE.

FREDERICK W. STEIN, OF CHICAGO, ILLINOIS, ASSIGNOR OF ONE-HALF TO THOMAS S. BOOTH, OF CHICAGO, ILLINOIS.

CARBURETER.

988,398.

Specification of Letters Patent. Patented Apr. 4, 1911.

Application filed November 22, 1909. Serial No. 529,207.

To all whom it may concern:

Be it known that I, FREDERICK W. STEIN, citizen of the United States, residing at Chicago, in the county of Cook and State of Illinois, have invented certain new and useful Improvements in Carbureters, of which the following is a specification.

This invention relates to improvements in carbureters of that type in which gas is generated in considerable volume from hydrocarbon oils for use especially in connection with gas engines.

The especial object of the improvements constituting the subject matter of this application is to provide for the thorough admixture of atmospheric air and the gases evolved from the hydrocarbon oil; to provide means for accurately controlling the quantity of air admitted to the apparatus, and means for effectively controlling the quantity of gas at a point adjacent to the engine on which it is to be used, and to provide means for storing the hydrocarbon oil and the gases evolved therefrom in substantial quantities, and to provide means for cleaning out the receptacles in which the gas is generated so as to remove any solids or impurities which may exist in the fluids or gas.

Other objects of simplicity and economy of construction and operation are embodied in the appliance illustrated in a preferred form in the accompanying drawing which forms a part of this application in which:

Figure 1 is a longitudinal section taken through the appliance complete; Fig. 2 is a transverse section of one of the tubes which form a feature of the appliance, and Fig. 3 is a vertical section on an enlarged scale of the final controlling device, which forms a feature of the apparatus involved in this application.

Referring to the drawing in detail, 4, 5, and 6, respectively, represent three tanks which as shown are arranged tandem in the same horizontal plane but may be arranged in any other manner which may be found convenient or desirable.

7 is a mixing chamber which communicates with the tank 6 at one side and at the

other side with the motor or other gas utilizing appliance which is not shown as same forms no part of this invention.

8 represents a vertically arranged pipe the lower end of which enters the tank 4 near its bottom and the upper end of which is provided with an adjustable conical valve 9 by which the amount of air entering the upper flared end of the pipe 8 may be controlled. The lower end of the pipe 8 communicates directly with a nozzle 10 which is formed with a plurality of helical coils the walls of which are furnished with numerous small perforations and which gradually decrease in cross-diameter toward the inner end of the nozzle 10.

In the upper edge of the tanks 4 and 5 are pipes 11 which are formed with a longitudinal slot 11^b extending substantially throughout the entire length of said pipe with the margins flanged as at 11^a. The inner ends of the pipes 11 are closed and their outer ends communicate through a suitable opening in the walls of the tanks 4 and 5 with conductor pipes 12, 12^a. At the bottom of each of the tanks 4 and 5 are faucets 13 by which the tanks may be drained if desired. The pipe 12 communicates with the nozzle 10 arranged in the tank 5 while the pipe 12^a communicates with the lower portion of the gas reservoir or tank 6.

Secured within the reservoir or tank 6 is a baffle plate 14 formed of corrugated sheet metal and so positioned that it will intercept the gases entering the reservoir from the tank 5 and the corrugated surface will aid in the mixing of the gas with the air in said reservoir and break up the gaseous fluid into eddies or whirls which facilitate the mixing operation.

In the mixing chamber 7 is arranged a perforated cylinder 15 which extends across the mixing chamber vertically and is designed to interrupt the passage of the gases through said mixing chamber to the outlet pipe 20. In the top of the mixing chamber 95 is secured a cap 16 which is provided with openings 16^a and has extending therethrough a stem 18^a of a valve 18 which is

seated in said cap. On the upper end of the valve stem 18^a is secured a nut 19 between which and the top of the cap and surrounding the stem is an expansion coiled spring 17 which normally holds the valve 18 on its seat and thus prevents the entrance of air to the cylinder 15.

In the operation and use of my improved carbureter gasoline is poured into the tank 10 4 by removing the screw cap 4^a until the tank is partly filled. The valve 9 is opened to permit air to enter the pipe 8 from which it escapes through the perforations in the coils of the nozzle 10 into the fluid in the 15 tank 4. The gas generated by the gasoline flows with the air that has escaped through the nozzle 10, arises to the top of the tank 4 and enters the pipe 11, passes out through the conductor pipe 12 and into the nozzle 10 in the tank 5. The gas escaping from the 20 perforations in the coils of the pipe 10 arises in the tank 5, enters the pipe 11 and passes out from said tank through the conductor pipe 12^a into the reservoir 6 from 25 the upper portion of which it escapes through the chamber 7 after coming in contact with the cylinder 15 and if the valve 18 is open with the air admitted to said chamber. It will be understood of course that 30 this action takes place when the gas is being exhausted or used from the pipe 20 thus creating a circulation through the several tanks, nozzles and pipes described. Inasmuch as the tank 5 provides for a substantial 35 quantity of gas it will be more or less agitated by the incoming gas and the outflowing gas and effective admixture of air and gas will take place in said tank. If, however, the gas should be too rich for the 40 best result the operator by opening the valve 18 can admit more air so that the gas flowing to the motor or gas user will be of the right quality.

If desired, valves of well known forms 45 may be placed in the pipes 12, 12^a, thus controlling the passage of the gas from one tank to the other.

The convolution of the walls of the nozzle 10 will cause a whirling of the air or gas 50 injected through said nozzle which, as is well known, contributes to a perfect mixture of gases.

The connections between the pipes 11, 12, and their respective tanks, will be made gas 55 and air tight by suitable packing devices and nuts of well known form.

The nozzle 10 in the tank 4 will serve as a filter for the incoming air thus arresting solids and particles which it is undesirable to have enter the gasoline and the corresponding nozzle in the tank 5 will have the same effect upon impurities in the

gas entering said tank from the tank 4. These nozzles therefore serve the purpose of conductors having an extended area and 65 also as filters, also to set up a whirling motion in the products introduced thereby.

Various other advantages of operation may be found in this invention which need not be set forth in this connection. 70

Having thus described my invention what I claim as new is:—

1. A carbureter composed of a plurality of communicating tanks, means for introducing a gas generating fluid into one of the tanks, and means for introducing air into said tank and a tapering nozzle arranged in said tank, said nozzle having its walls in the form of spirals and having perforations therein for the purpose set forth, 80 and means for conducting the gases generated in said tank into a suitable reservoir. 75

2. A carbureter composed of a plurality of communicating tanks, means for introducing a gas generating fluid into one of the tanks, means for introducing air into said tank, means for conducting the gases generated in said tank into a second tank, tapering nozzles arranged in said tanks, and connected with the inlets of said tanks, said 90 nozzles having spirally formed perforated walls, and means for conducting the gases generated in said tanks into a suitable reservoir. 85

3. A carbureter comprising a gas generating tank, a reservoir and an intermediate tank, pipes connecting the generating tank with the intermediate tank, and the intermediate tank with the reservoir, said pipes having one end projecting horizontally into 100 their respective tanks and provided with longitudinal slots, a baffle plate arranged in said reservoir opposite the inlet of its respective pipe, and a mixing chamber communicating with the reservoir. 95

4. A carbureter comprising a generating tank, an air inlet pipe for the tank, a valve for said pipe, a perforated nozzle for the inlet of said pipe within said tank, said nozzle having its walls in the form of spirals, 110 an intermediate tank, a pipe connecting said tanks having its upper end arranged horizontally in the generating tank and provided with a longitudinal slot, a helical tapering nozzle controlling the entrance of said pipe in the intermediate tank, a reservoir connected with the intermediate tank, a baffle plate in said reservoir arranged opposite the inlet orifice, and a mixing chamber 115 communicating with said reservoir. 105

5. A carbureter comprising a plurality of tanks, means for introducing a gas generating fluid in one of said tanks, means for introducing air into said tank, a perforated

helical nozzle for the air inlet, a longitudinal slotted pipe arranged horizontally in said tank and communicating with a second tank, a spiral nozzle in the second tank, a longitudinally slotted pipe arranged horizontally in the second tank, and communicating with a reservoir, a baffle plate in the reservoir arranged opposite the inlet, a mixing chamber communicating with the reser-

voir, a perforated cylinder in said chamber, 10 and a valve for the chamber.

In testimony whereof I affix my signature in the presence of two witnesses.

FREDERICK W. STEIN.
